DESIGN FOR A BUILDING

Edwina S. Johnston and William P. Whitney,
Chicago, Ill., assignors to Tank Car Stations,
Inc., Chicago, Ill., a corporation of New York

Application June 30, 1941, Serial No. 101,817

Term of patent 3½ years

To all whom it may concern:

Be it known that we, Edwina S. Johnston and William P. Whitney, citizens of the United States, residing at Chicago, in the county of Cook and State of Illinois, have invented a new, original, and ornamental Design for a Building, of which the following is a specification, reference being had to the accompanying drawing, forming part thereof.

The figure of the drawing is a perspective view of a building embodying our new design.

The main building walls, obstructed by the wing portions in the view shown in the drawing, are substantially flat, rectangular, vertical surfaces, and the rear of the wing portions have substantially the same outline as in the view shown.

We claim:

The ornamental design for a building, substantially as shown and described.

EDWINA S. JOHNSTON.
WILLIAM P. WHITNEY.
